NILS H. ANDERSON, OF MIDDLETOWN, CONNECTICUT, ASSIGNOR TO THE NOISELESS TYPEWRITER COMPANY, OF MIDDLETOWN, CONNECTICUT, A CORPORATION OF CONNECTICUT.

TYPE-WRITING MACHINE.

1,175,916.

Specification of Letters Patent. Patented Mar. 21, 1916.

Application filed May 16, 1910. Serial No. 561,520.

To all whom it may concern:

Be it known that I, NILS H. ANDERSON, a citizen of the United States, residing at Middletown, in the county of Middlesex 5 and State of Connecticut, have invented certain new and useful Improvements in Type-Writing Machines, of which the following is a full, clear, and exact description, such as will enable others skilled in the art to 10 which it appertains to make and use the same.

This invention relates to ribbon mountings for typewriting machines, and with regard to the more specific features thereof 15 to the ribbon spool construction and the parts to which the ends of the ribbon are secured for attaching the same to the spools.

One of the objects of the present invention is to provide mechanism of the above 20 character whereby the placing of the ribbon upon the spool or ribbon support in operative position is assured.

Another object is to provide mechanism of the above character that will be practical 25 in construction and efficient in operation.

A further object is to provide mechanism of the above character which will be inexpensive to manufacture.

A further object is to provide a self-contained 30 ribbon spool with improved forms of ribbon core and grip for attaching the ends of the ribbon thereto.

A further object is to provide mechanism of the last mentioned character whereby the 35 placing of said parts in proper operative position is assured.

Other objects will be in part obvious and in part hereinafter pointed out.

The invention accordingly consists in the 40 features of construction, combination of elements and arrangement of parts which will be exemplified in the construction herein-after set forth, and the scope of the application of which will be indicated in the following claims.

In the accompanying drawings, wherein are shown a few of the various possible embodiments of this invention, Figure 1 illustrates a preferred embodiment of the present invention with portions of a ribbon mounting in disassembled position sufficient to 50 illustrate the invention as applied thereto; Figs. 2 and 8 are modifications showing different embodiments of the invention;

Figs. 4 and 5 are plan and sectional elevation views, respectively, of a further modification; Fig. 6 is a perspective view of the driving spindle shown in Fig. 5; Fig. 7 is the blank from which the preferred form of ribbon core is made; Fig. 8 is the blank 60 from which the preferred form of ribbon grip is made; Figs. 9 and 10 are respective views of modified forms of ribbon grips; Fig. 11 is a perspective view of a modified form of ribbon core with parts broken away 65 to show certain details of construction thereof.

Similar reference characters refer to similar parts throughout the several views of the drawings.

While the present invention is herein shown and described in its preferred form as applied to ribbon mountings used in that style of typewriting machine known as the Noiseless typewriter, it is to be understood 70 that the various features of this invention may be applied to other well known forms of machines as well. For instance, the ribbon mounting used in the Underwood typewriting machine is shown with the invention 75 applied thereto by the modification in Figs. 4, 5 and 6. A number of well known makes of typewriting machines, such as those above mentioned, for example, comprise in the ribbon feed mechanism a main driving shaft 80 operated from the carriage spring drum driving mechanism adapted to be operatively connected with the ribbon driving spindles disposed at opposite sides in the frame of the machine. Upon these ribbon 85 driving spindles are placed ribbon spools, one of which is adapted to be connected to its spindle by suitable alternating clutch mechanism or positively connected to its spindle at all times, the spindle alternately 90 being connected and disconnected with the main driving member whereby it is rotated positively to wind the ribbon thereupon in superimposed layers as the carriage is fed along in a letter spacing direction, the opposite spool or spool and spindle being free 100 to rotate, allowing the ribbon to unwind therefrom. By operating the clutch mechanism between the main driving shaft and the ribbon spool the rotation of the ribbon 105 spool may be reversed so as to rewind the ribbon upon the spool from which it has previously been unwinding, that is, the clutch

mechanism alternately clutches and releases the ribbon spools from their connections with the driving mechanism to wind and unwind the ribbon in opposite directions. As is well known to those familiar with the operating of typewriting machines of the above mentioned character, among others, the ribbon is usually received from the manufacturer already wound or coiled upon a core or spool of one form or another whereby the same may be conveniently slipped over the driving spindle, and the free end of the ribbon drawn across, through suitable ribbon guides, past the printing point, to the ribbon spool at the opposite side of the machine, and secured thereto in any well known manner, whereupon the ribbon is ready for operation to be unwound from the first spool and rewound upon the other, the motive power being exerted upon the latter as the carriage is fed along in a letter spacing direction. It is often desirable to actuate the ribbon reverse when the ribbon is nearly unwound from one spool, even when the machine is provided with an automatic reverse, as the same cannot always be relied upon to reverse the feed of the ribbon, and the operator must be constantly on the alert to prevent the ribbon from entirely unwinding from one of the spools, producing a drag upon the carriage feeding mechanism, thereby causing the letters to pile up on each other during the operation of the machine. In order to avoid these and other objections the operator may reverse the feed of the ribbon before it has been entirely unwound from one of the spools. Now if the ribbon spool is placed on the ribbon spool spindle or support in proper position the ribbon will rewind in a normal manner upon the now positively driven spool from which it has just been unwound, but should the spool be placed upon the spindle in inverted position, as is frequently done by an inexperienced or careless operator, when the ribbon feed is reversed before the ribbon has been entirely unwound from the spool the rotation of the spool will then be in the opposite relative direction from which it should, thereby causing the ribbon first further to unwind and then rewind upon itself. This further unwinding will entangle the ribbon within the ribbon spool and stop the feed of the ribbon as the carriage moves in a letter spacing direction, thereby allowing several impressions to be made upon the ribbon at the same point which would exhaust the ink from and in all probability form a hole in the ribbon at that point. It is therefore one of the objects of this invention to provide a core or that part upon which the ribbon is wound as supplied by the manufacturer, with means for positively assuring the same being placed upon the

ribbon driving spindle in proper position, or in other words, prevent the part from being placed in inverted operative position.

Referring now to the drawings, particularly to Fig. 1, in which a preferred embodiment of this invention is shown, 1 and 2 represent respectively the right and left hand ribbon spool supporting spindles disposed at opposite sides of the machine, upon which are mounted ribbon spool flanges 3 and 4, respectively, provided with hollow central cylindrical hubs 5 and 6 within which are a plurality of spring arms 7 adapted to engage the covers or upper heads 8 by snapping into engagement therewith through a central opening 9, shown in dotted lines, within hollow bosses 10, by which the covers may be conveniently handled. Each of the hubs 5 and 6 is provided with a plurality of vertically disposed slots 11 and 12, the slots 11 being wider than the slots 12 and in opposite relation to each other, that is, these hubs are rights and lefts, the narrow slot 12 at one side of the machine being at the opposite side of the slot 11 from the slot 12 at the other side of the machine. A core 13 to which one end of a ribbon 14 is adapted to be secured, as by means of outwardly punched teeth 15, is preferably made from a strip of sheet metal, the blank of which is shown in Fig. 7. For the sake of clearness the ribbon 14 is shown entirely unwound from the ribbon core. The ends 16 of the blank are turned inwardly to form an inwardly projecting flange 17 of a width to engage the narrow slot 12 of the hub, and near one end of the strip are punched a plurality of inwardly projecting tongues or lugs 18 wider than the slot 12 of the hub, but of a width to enter the wide slot 11 thereof. The distance between the flange 17 and tongues 18 measured in one direction around the core is substantially equal to the distance between the slots 11 and 12 of the hub. It is thus seen that the flange 17 and inwardly projecting lugs 18 are adapted to engage respectively the narrow slot 12 and the wide slot 11 in the hub 6, as shown in Fig. 1. These parts 17 and 18 being relatively close together, or in a position other than diametrically opposite, positively prevent the core 13 from being inverted and slipped over the hub 6, yet will allow the same to be inverted and slipped over the opposite hub 5, in which it will be in operative position as the hubs 5 and 6 are driven alternately in opposite directions. For the opposite or free end of the ribbon 14 to secure it to its spool is provided a ribbon grip 19 which comprises a short strip of sheet metal, as shown in blank form in Fig. 8, provided at each end with a plurality of fastening teeth 20 which are adapted to be bent over the end of the

ribbon to securely clamp the same thereto. From the central part of this strip are two punched up tongues 21 which extend inwardly in the same vertical plane and are 5 then bent at right angles thereto in opposite directions thereby to form a T-shaped retaining member adapted to engage either of the slots in either hub 5 or 6, depending upon the location of the ribbon wound upon 10 the core 13. From the above it will be seen that the ribbon core with the ribbon wound thereon as received from the manufacturer is adapted to be placed upon either of the hollow cylindrical hubs 5 or 6 and locked 15 in engagement therewith, whereby the hub and core rotate simultaneously by means of the projecting lugs 18 engaging the wider slot 11 while the inwardly bent ends 17 engage the narrow slot 12, the construction and arrangement of these parts being such that the coiled ribbon is positively prevented from being placed upon its support in an inverted operative position. The ribbon is then partially unwound in the usual 20 manner and slipped through the ribbon guides at the printing point and drawn across to the grip 19 which is placed upon the hub of the ribbon support, after which the covers 8 are snapped into place to hold 25 these parts in operative position.

Figs. 2 and 3 illustrate modified forms of the device shown in Fig. 1. In Fig. 2, instead of providing two slots in the hub 6, an outwardly projecting pin 22 and slot 23 30 are adapted to co-act respectively with a hollow rib 24 and an inwardly projecting tongue 25 formed by the flanged ends of the core as in Fig. 1. Fig. 3 is somewhat similar in general construction, except that the co- 35 acting means for assuring the core being placed in proper operative position consists in providing the flange 4 of the spool with a hole 26 adapted to be engaged by a projection 27 on the core. Obviously if the 40 core were inverted in either construction it would be impossible to place it upon the spool in operative position. The upper projection 27 engages the corresponding hole 26 on the opposite ribbon spool.

Referring now to the modification shown 45 in Figs. 4, 5 and 6, Fig. 4 illustrates in plan view the opposite spools as used on the Underwood machine, each of which comprises a lower flange 28 and an upper flange 50 29 connected by a hollow cylindrical hub 30. Within the hub and through both heads are provided a relatively large hole 31 and a smaller hole 32 closely adjacent thereto, adapted to be engaged respectively by large 55 and small pins 33 and 34 carried on a driving spindle 35 shown in Fig. 6. These 60 holes and pins are so arranged on the respective parts as to permit the spool being placed in proper operative position upon either spindle, yet positively prevent the rib- 65

bon being inverted and placed thereupon, as the larger pin 33 would then contact with the smaller hole 32, thereby to prevent the spool falling into proper place thereon. Such a condition, of course, would immediately be noted by the operator, as a feed 70 of the ribbon would not then take place.

In Fig. 9, 36 illustrates a modified form of ribbon grip in closed position. This grip is preferably of soft metal that may be 75 easily bent, and when in open position pointed teeth 37 are separated a sufficient distance to permit the free end of the ribbon being inserted therebetween, after which the grip is squeezed between the 80 fingers to cause the teeth to penetrate the ribbon. The grip is then inserted within the central hub with the ribbon passing through one of the slots, the grip being of greater width than the slot it is thereby prevented 85 from being pulled out. In this manner the spool may be rotated to entirely unwind the ribbon and then rewind thereupon by rotating in the same direction, without danger 90 of the ribbon becoming detached from its securing means.

Fig. 10 illustrates a further modification of a ribbon grip which comprises a body portion 38 bent in the form of an arc to conform to the outer periphery of the ribbon spool hub, having at each side thereof a plurality of outwardly projecting bent-back teeth 39 and a plurality of inwardly projecting T-shaped lugs 40 on its inner side. The lugs 40 are adapted to engage one of 100 the slots, preferably the narrow one, in either hub, in very much the same manner as the lugs 21 shown in Fig. 8, thereby to hold the grip in operative position with the hub to rotate therewith. In securing the 105 ribbon thereto it is placed adjacent the outer surface of the grip and pulled against the teeth, thereby to cause the same to penetrate the ribbon. The teeth may then be pressed down firmly to clamp the same in place. 110 In use, should the ribbon become entirely unwound from the ribbon grip it may be rewound upon the same in the opposite direction by the continued rotation of the spindle, as the ribbon could not possibly 115 pull out from engagement with the teeth at one side before it would be caught by the teeth at the opposite side, thereby to continue its hold thereupon.

Fig. 11 illustrates a modified form of core, 120 which is preferably made of wood, paper or fiber in the form of a cylindrical tube 41. At any point about its upper and lower ends are cut small notches adapted to be engaged by the bent-over ends 42 of the dog 43. This 125 dog combines the function of attaching the ribbon to the grip, as by means of teeth 44, and also of locking the same in operative position with the spool by means of the inwardly projecting lugs 45. Adjacent the 130

dog 43 is provided a pin 46 extending slightly within the interior of the core, being adapted to engage the slot 12 in the hub. It will thus be seen that an article 5 of this kind may act either as a grip or a ribbon core and be slipped over either hub 5 or 6 in proper position. When acting as a core it is positively prevented from being placed in inverted operative position 10 upon the spool by reason of the projections 45 and 46 engaging the slots 11 and 12 respectively.

As the operation and manner of use of these several devices are believed to be clear 15 from the above description, a specific discussion thereof, it is thought, may be omitted.

It is thus seen that this invention provides, among others, for all the objects and 20 advantages above set forth.

As many changes could be made in the above construction and many apparently widely different embodiments of this invention could be made without departing from 25 the scope thereof, it is intended that all matter contained in the above description or shown in the accompanying drawings shall be interpreted as illustrative and not in a limiting sense.

Having described my invention, what I 30 claim as new and desire to secure by Letters Patent is:

1. In a device of the character described, in combination, a pair of rotatable supports, 35 a ribbon attaching member, and engaging means permitting the coöperative association of said member with one of said supports, and, upon inversion, with the other of said supports, and preventing operative 40 association of said member with one of said supports in both uninverted and inverted positions.

2. In a device of the character described, in combination, a rotatable ribbon supporting 45 means, a cylindrical core upon which the ribbon is adapted to be wound having an inwardly bent lug adapted to engage said ribbon supporting means whereby said parts rotate together, and means assuring said 50 core being placed in operative position upon said supporting means.

3. In a device of the character described, in combination, a self-contained ribbon spool, a cylindrical sheet metal core, ribbon 55 fastening means thereon, means associated therewith adapted to engage said spool whereby said parts will rotate together, and means assuring said core being placed in operative position upon said spool.

60 4. In a device of the character described, in combination, right and left rotatable ribbon supporting means, a part upon which the ribbon is wound adapted to engage either of said supporting means whereby 65 they may rotate together, and means pre-

venting said part from being placed in inverted operative position upon either of said rotatable supporting means.

5. In a device of the character described, in combination, right and left rotatable 70 ribbon supporting means, a part upon which the ribbon may be wound adapted to engage either of said supporting means whereby they may rotate together, means assuring said part being placed in operative position 75 upon either of said rotatable supporting means, and a ribbon grip adapted to secure the free end of a ribbon to the other of said ribbon supporting means.

6. In a device of the character described, in combination, right and left rotatable ribbon supporting means, a part upon which the ribbon is wound adapted to engage either of said supporting means whereby they may rotate together, means assuring said 85 part being placed in operative position upon either of said rotatable supporting means, and a sheet metal grip to which the free end of the ribbon is adapted to be clamped engaging the other of said ribbon supporting 90 means and held against rotation thereon.

7. In a device of the character described, in combination, a right and left rotatable ribbon supporting means comprising cylindrical hubs having recesses therein, and a 95 part upon which a ribbon may be wound having means associated therewith to engage the recesses in said supporting means, the construction and arrangement of said recesses and part assuring said part being 100 placed in operative position.

8. In a device of the character described, in combination, right and left rotatable ribbon spools having recesses therein, a cylindrical sheet metal core, ribbon fastening 105 means thereon, and lugs associated therewith whereby the core may be placed upon said spools to rotate therewith, the construction and arrangement of said lugs and recesses being such as to prevent said core 110 from being placed upon either spool in inverted operative position.

9. In a device of the character described, in combination, right and left rotatable ribbon spools having recesses therein, a cylindrical sheet metal core having outwardly punched teeth whereby the ribbon may be secured thereto, and means associated therewith whereby the core may be placed upon said spools to rotate therewith, the construction and arrangement of said means and recesses being such as to assure said core being placed upon either spool in operative position.

10. In a device of the character described, 125 in combination, right and left rotatable cylindrical ribbon spools, each having a plurality of recesses therein, a cylindrical core adapted to be placed upon either of said ribbon spools, means associated therewith 130

- whereby said parts may rotate together, and means on said core adapted to engage one of said recesses but not the other in such a manner as to prevent the core from being placed upon either spool in inverted operative position.
11. In a device of the character described, in combination, right and left rotatable cylindrical ribbon spools, each having a plurality of recesses therein, a cylindrical core adapted to be placed upon either of said ribbon spools, means associated therewith whereby said parts may rotate together, means on said core adapted to engage one of said recesses in such a manner as to assure the core being placed upon either spool in operative position, and means associated with said core for attaching the ribbon thereto.
12. In a device of the character described, in combination, right and left rotatable cylindrical ribbon spools, each having a plurality of recesses therein, a sheet metal cylindrical core adapted to be placed upon either of said ribbon spools, means associated therewith whereby said parts may rotate together, means on said core adapted to engage one of said recesses in such a manner as to assure the core being placed upon either spool in operative position, means associated with said core for attaching the ribbon thereto, and means adapted to secure the free end of said ribbon to the opposite spool.
13. In a device of the character described, in combination, right and left rotatable cylindrical ribbon spools, each having a plurality of recesses therein, a sheet metal cylindrical core adapted to be placed upon either of said ribbon spools, means associated therewith whereby said parts may rotate together, lugs on said core adapted to engage one of said recesses but not the other in such a manner as to assure the core being placed upon either spool in operative position, means associated with said core for attaching a ribbon thereto, and a sheet metal grip adapted to secure the free end of a ribbon to the opposite ribbon spool.
14. In a device of the character described, in combination, a rotatable ribbon spool having a central hub provided with a plurality of slots of different width, a ribbon core upon which the ribbon is wound having inwardly bent projections adapted to engage said slots, the construction and arrangement of said projections and slots being such as to positively prevent the core from being placed upon the ribbon spool in an inverted operative position.
15. In a device of the character described, in combination, right and left ribbon spools disposed at opposite sides of the machine having removable heads and cylindrical hubs, a plurality of openings of unequal size in each of said hubs, and a ribbon core provided with a plurality of inwardly projecting means adapted to engage said openings, said openings and means being so arranged and constructed as to positively assure the core being placed in operative position upon either of said spools, said core having means associated therewith whereby one end of the ribbon may be secured thereto.
16. In a device of the character described, in combination, right and left ribbon spools disposed at opposite sides of the machine having removable heads and cylindrical hubs, a plurality of slots of unequal width in each of said hubs, and a ribbon core provided with a plurality of inwardly projecting lugs adapted to engage said slots, said slots and lugs being so arranged and constructed as to positively assure the core being placed in operative position upon either of said spools, said core having outwardly punched teeth to which one end of said ribbon may be secured.
17. In a device of the character described, in combination, right and left ribbon spools disposed at opposite sides of the machine having removable heads and cylindrical hubs, a plurality of slots of unequal width in each of said hubs, a ribbon core provided with a plurality of inwardly projecting lugs of different size adapted to engage said slots, said slots being so arranged and constructed as to positively assure the core being placed in operative position upon either of said spools, said core having outwardly punched teeth to which one end of the ribbon may be secured, and means for securing the opposite end of said ribbon to the opposite ribbon spool.
18. In a device of the character described, in combination, right and left ribbon spools disposed at opposite sides of the machine having removable heads and cylindrical hubs, a plurality of slots of unequal width in each of said hubs, a ribbon core provided with a plurality of inwardly projecting lugs of similar widths adapted to engage said slots, said slots being so arranged and constructed as to positively assure the core being placed in operative position upon either of said spools, said core having outwardly punched teeth to which one end of the ribbon may be secured, and a sheet metal ribbon grip having outwardly punched teeth to which the free end of said ribbon may be secured and inwardly punched lugs whereby the grip may be secured in operative position upon said spool.
19. A ribbon grip comprising a piece of sheet metal having backwardly bent teeth at the opposite ends thereof, and inwardly projecting means on the upper and lower side whereby the grip may be secured to the part adapted to carry the same.
20. In a typewriting machine, in combina-

6
tion, a pair of spaced ribbon supports and a ribbon core, said elements having complementary means to enable the mounting of said core on either of said supports but only 5 in relatively opposite upright and inverted positions.

21. In a typewriting machine, in combination, a pair of spaced rotatable ribbon supports and a ribbon core, said elements 10 having complementary means to enable

mounting said core on one of said supports only in a relatively upright position and on the other of said supports only in a relatively inverted position.

In testimony whereof I affix my signature, 15
in the presence of two witnesses.
